PARK, MARYLAND.

NUT LOCK.

Application filed November 12, 1925. Serial No. 68,625.

To all whom it may concern:

Be it known that I, ROBERT R. CHILDS, a citizen of the United States, residing at Roanoke, in the county of Roanoke and State of Virginia, have invented certain new and useful Improvements in Nut Locks, of which the following is a specification, reference being had to the accompanying drawings.

This invention relates to certain improvements in nut locks and it is an object of the invention to provide a device of this kind wherein the bolt is provided with means co-acting with the nut to hold the same against retrograde rotation and particularly upon vibration of the work to which the bolt is applied.

Another object of the invention is to provide a device of this kind which is particularly adapted for use in connection with motors and movable structures, such as aeroplanes and the like.

The invention consists in the details of construction and in the combination and arrangement of the several parts of my improved nut lock whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a view partly in elevation and partly in section of a nut lock constructed in accordance with an embodiment of my invention;

Figure 2 is a view in top plan of the structure as illustrated in Figure 1;

Figure 3 is a fragmentary view in perspective of the outer or free end portion of the bolt;

Figure 4 is a view in perspective of the locking member unapplied.

As disclosed in the accompanying drawing, B denotes a bolt of a conventional type upon the outer or free end portion of which is adapted to be threaded the usual nut N. The outer or free end portion of the bolt

B is recessed, as at 1, with the inner end or base 2 of said recess having its inner straight edge substantially radial to the bolt B proper while the side wall 3 is disposed toward the free end of the bolt B on a slight incline and inwardly of the base 2.

The locking member L constitutes a block which substantially fills the cut out portion 1 except that the inner face thereof has its major portion disposed, as at 4, on a slight inward incline, said portion 4 extending inwardly of the member L beyond the center of such face. This inclined portion 4 provides a space 5 when the member L is in applied position so that upon vibration of the work with which the bolt B is engaged, the member L will have a tendency to rock resulting in increased frictional contact with the bore of the nut N and thus holding the same against retrograde movement. The remaining portion of the inner face of the member L is disposed on an incline similar to the inclined wall 3 of the bolt B and adapted to have close contact therewith at all points whereby effective means are provided for assuring the member L being maintained in applied position and particularly when the nut N is operatively engaged with the bolt.

When the nut N has a tendency to unscrew the locking member or block L will rock sideways and the threaded engagement between the nut N and the member or block L is such, as the nut N moves outwardly of the bolt B, to cause the member or block L to move outwardly and such outward movement of the member or block L due to the coacting inclined faces 3 and 4 will result in the member or block L moving outwardly in a radial direction and having effective wedging action on the nut N.

From the foregoing description it is thought to be obvious that a nut lock constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself

to the precise arrangement and formation of the several parts herein shown in carrying out my invention in practice except as hereinafter claimed.

5 I claim:—

A nut lock comprising a bolt having a portion of its threaded free end cut away to form a longitudinal recess with a flat surface slightly inclined in longitudinal direction, 10 the recess being deeper at the bottom than at the top; a block inserted in the recess, substantially filling the same, the inner face of the block having its major portion inclined for close contact with the inclined surface 15 of the recess of the bolt, the remaining por-

tion of said inner face of the block being beveled, and a nut having threaded engagement with the bolt and the applied block, unscrewing rotation of the nut rocking the block in a direction transversely of the bolt 20 and moving the block outwardly of the inclined surface of the recess of the bolt, said outward movement of the block causing the block to be moved substantially radial of the bolt into wedging action upon 25 the nut.

In testimony whereof I hereunto affix my signature.

ROBERT R. CHILDS.
